UNITED STATES PATENT OFFICE

ADOLPH L. KEUNE, OF CARLINVILLE, ILLINOIS

COMBINED TRACK AND COUPLING ATTACHMENT

Application filed April 12, 1932. Serial No. 604,815.

This invention relates to a combined track and coupling attachment for doors of the slidably suspended type, and has for its object to provide, in a manner as hereinafter set forth, an attachment of the class referred to for preventing the outward swinging of the door with respect to the door frame, the warping and springing of the door, and further providing for easily shifting the latter when opening and closing it.

Further objects of the invention are to provide, in a manner as hereinafter set forth, an attachment of the class referred to which is simple in its construction and arrangement, 15 strong, durable, compact, thoroughly efficient in its use, readily installed, and comparatively inexpensive to manufacture.

To the above ends essentially and others which may hereinafter appear, the invention 20 consists of such parts, and such combination of parts which fall within the scope of the invention as claimed.

In the drawing:

Figure 1 is an elevation looking towards 25 that face of a slidably suspended door provided with one of the elements of the attachment.

Figure 2 is an elevation of the attachment with one of the coupling elements omitted.

30 Figure 3 is a sectional plan of a door and a door frame showing the adaptation therewith of an attachment in accordance with this invention.

Figure 4 is a section on line 4—4 Figure 3.

35 Figure 5 is a section on line 5—5 Figure 2 with a fragmentary part of the door end frame illustrated.

Figure 6 is a section on line 6—6 Figure 3.

Referring to the drawing, 1 and 2 indicate 40 the sides and 3 the sill of a door frame. A slidably suspended door for opening and closing the door opening provided by the frame is indicated at 4. Secured to one side of the door frame in proximity to the sill 3, 45 as well as projecting from the door opening is an adjustable coupling element 5. Secured to that face of the door 4 which is to oppose the door frame and in proximity to the bottom thereof is a track forming element 6 disposed transversely of said face.

The element 5 includes a holder plate 7 standing on its lower lengthwise edge and formed with an angularly disposed outer end part 8. One face of plate 7 is formed with lengthwise disposed spaced parallel ribs 9 extending from the inner end to a point removed from the end part 8. The ribs are flush with the side edges of plate 7. Holdfast devices 10 are employed for fixedly securing plate 7 to the side of the door frame. The 55 plate 7 is also formed with an opening 11 having a threaded wall.

The element 5 also includes an adjustable coupling arm 12 formed of a pair of parts 13, 14, the former being of greater length 55 than the latter. The part 14 is disposed at right angles to the outer end of part 13 and extends in an opposite direction with respect to the outer end part 8 of plate 7. The part 13 is formed with a lengthwise slot 15 for the 70 passage of a binding screw 16 which engages with the threaded wall of opening 11. The slot 15 provides for the adjusting of coupling arm 12 lengthwise with respect to plate 7, and screw 16 and threaded wall of opening 11 75 coact to secure arm 12 in its adjusted position. The arm 12 projects beyond the outer end of plate 7 and is confined between the ribs 9.

Fixedly secured by the holdfast devices 17 80 against the outer face of part 14 of arm 12 is a supporting element 18 formed of a housing 19, open at each end and having its front wall formed with an opening 20 to provide a clearance for a purpose to be referred to. Extending through the side walls of housing 19 85 and secured thereto by a holding nut 21 is a headed, threaded bolt 22 which provides a shaft for a revoluble roller 23.

The element 6 is secured to the door and 90 comprises an oblong plate 24 standing on one lengthwise edge and of the desired width and length. The plate 24 is provided at each end with a stop flange 25 directed towards and abutting the door. That face of plate 95 24 which is to oppose the door has at the longitudinal median thereof a spacing rib 26 extending from one flange 25 to the other flange 25 and abutting the door. The rib 26 extends through the openings 20 in the front 100

wall of the housing 19 and such front wall overlap the top and bottom of plate 24 when the attachment is set up relative to the door and door frame. The element 6 is secured to door 4 by holdfast devices 27 which extend through the body of plate 24, rib 26, plates 28 and engage in the body of the door. The plates 28 are countersunk in the door body. The holdfast devices 27 are countersunk in the plate 24. The flanges 25 coact with the housing 19 to prevent the separation of the elements 6 and 18 and also act as stops to limit the shifting movement of the door in either direction.

The elements 5, 6 and 18 when set up couple the door with the door frame and prevent the former from swinging away from the latter, as well as preventing the warping or springing of the door and further enables the latter to be readily shifted in the desired direction.

What I claim is:—

1. A combined track and coupling attachment for an end portion of a slidably suspended door comprising, a coupling element adapted to be secured to a side of the door frame, a supporting element fixedly secured to the outer end of said coupling element and including a housing and a revolute roller in the latter, and a track element adapted to be secured to and having a portion spaced from the door, said portion being overlapped by one wall of said housing and having one face thereof bearing against the roller of said supporting element.

2. A combined track and coupling attachment for an end portion of a slidably suspended door comprising, a coupling element adapted to be secured to a side of the door frame, a supporting element fixedly secured to the outer end of said coupling element and including a housing and a revolute roller in the latter, a track element adapted to be secured to and having a portion spaced from the door, said portion being overlapped by one wall of said housing and having one face thereof bearing against the roller of said supporting element, said coupling element including an adjustable coupling arm, and said supporting element being fixedly secured to said arm.

3. A combined track and coupling attachment for an end portion of a slidably suspended door comprising, a coupling element adapted to be secured to a side of the door frame, a supporting element fixedly secured to the outer end of said coupling element and including a housing and a revolute roller in the latter, and a track element adapted to be secured to and having a portion spaced from the door, said portion being overlapped by one wall of said housing and having one face thereof bearing against the roller of said supporting element, said track element including means coacting with the supporting

element for limiting the shifting movement of the door in either direction.

4. A combined track and coupling attachment for an end portion of a slidably suspended door comprising, a coupling element adapted to be secured to a side of the door frame, a supporting element fixedly secured to the outer end of said coupling element and including a housing and a revolute roller in the latter, a track element adapted to be secured to and having a portion spaced from the door, said portion being overlapped by one wall of said housing and having one face thereof bearing against the roller of said supporting element, said coupling element including an adjustable coupling arm, and said supporting element being fixedly secured to said arm, said track element including means coacting with the supporting element for limiting the shifting movement of the door in either direction.

5. A combined track and coupling attachment for an end portion of a slidably suspended door comprising, a coupling element adapted to be secured to a side of the door frame, a supporting element fixedly secured to the outer end of said coupling element and including a housing and a revolute roller in the latter, a track element adapted to be secured to and having a portion spaced from the door, said portion being overlapped by one wall of said housing and having one face thereof bearing against the roller of said supporting element, and said portion of said track element having its other face formed with a lengthwise rib, the said walls of the housing having an opening for the passage of the rib.

6. A combined track and coupling attachment for an end portion of a slidably suspended door comprising, a coupling element adapted to be secured to a side of the door frame, a supporting element fixedly secured to the outer end of said coupling element and including a housing and a revolute roller in the latter, a track element adapted to be secured to and having a portion spaced from the door, said portion being overlapped by one wall of said housing and having one face thereof bearing against the roller of said supporting element, said coupling element including an adjustable coupling arm, said supporting element being fixedly secured to said arm, said portion of said track element having its other face formed with a lengthwise rib, and the said walls of the housing having an opening for the passage of the rib.

7. A combined track and coupling attachment for an end portion of a slidably suspended door comprising, a coupling element adapted to be secured to a side of the door frame, a supporting element fixedly secured to the outer end of said coupling element and including a housing and a revolute roller

in the latter, a track element adapted to be secured to and having a portion spaced from the door, said portion being overlapped by one wall of said housing and having one face
5 thereof bearing against the roller of said supporting element, said track element including means coacting with the supporting element for limiting the shifting movement of the door in either direction, said portion
10 of said track element having its other face formed with a lengthwise rib, and the said walls of the housing having an opening for the passage of the rib.

8. A combined track and coupling attachment for an end portion of a slidably suspended door comprising, a coupling element adapted to be secured to a side of the door frame, a supporting element fixedly secured to the outer end of said coupling element
15 and including a housing and a revoluble roller in the latter, a track element adapted to be secured to and having a portion spaced from the door, said portion being overlapped by one wall of said housing and having one
20 face thereof bearing against the roller of said supporting element, said coupling element including an adjustable coupling arm, said supporting element being fixedly secured to said arm, said track element including means
25 coacting with the supporting element for limiting the shifting movement of the door in either direction, said portion of said track element having its other face formed with a lengthwise rib, and the said wall of the housing
30 having an opening for the passage of the rib.

35

In testimony whereof, I affix my signature
hereto.
